CRIMPING MACHINE

Edwin Floyd, Jr., Harrisburg, and Rudolph J. Perme, York, Pa., assignors to AMP Incorporated, Harrisburg, Pa.

Filed Sept. 9, 1958, Ser. No. 759,910

1 Claim. (Cl. 153—1)

This invention relates to a machine for crimping electrical connectors and contacts onto conductors to form an electrical joint.

It is an object of this invention to provide such a machine that is small and compact.

It is also an object of this invention to provide a one-cycle clutch in such a machine whereby the operating dies will go through one stroke, return to their initial position and remain inactive until the operator causes it to be actuated again.

It is also an object of this invention to provide a magazine fed machine for storing and feeding a plurality of independent connectors (as opposed to connectors in strip form) in such a machine.

It is an object of this invention to provide an automatic machine whereby the connector is positioned and held stationary while a pair of dies come together to make a crimped connection to insure proper positioning of the connector during the crimping stroke.

Machines for applying connectors in strip form have the advantage of being able to use the strip to successively position the foremost connector during the feeding cycle.

However a machine for crimping independent connectors is deprived of this feeding advantage. Thus it is an object of this invention to provide a machine for storing a plurality of independent connectors and feeding them seriatim to the crimping dies.

Other objects and attainments of the present invention will become apparent to those skilled in the art upon a reading of the following detailed description when taken in conjunction with the drawings in which there is shown and described an illustrative embodiment of the invention; it is to be understood, however, that this embodiment is not intended to be exhaustive nor limiting of the invention but is given for purposes of illustration in order that others skilled in the art may fully understand the invention and the principles thereof and the manner of applying it in practical use so that they may modify it in various forms, each as may be best suited to the conditions of a particular use.

In the drawings:

FIGURE 1 illustrates a machine embodying principles of this invention as shown in perspective;

FIGURE 2 is a plan view of the device shown in FIGURE 1 partially broken away, illustrating the driving mechanism when the dies are in their open or inoperative position;

FIGURE 3 is a view similar to FIGURE 2 showing the dies in closed position;

FIGURE 4 is a side plan view of the device shown in FIGURES 1-3;

FIGURES 5-7 show the mechanism for adjusting the dies relative to the driving means;

FIGURES 8-10 illustrate the one cycle clutch in various positions of its cycle;

FIGURE 11 is a sectional view showing the relationship of the clutch to the fly wheel;

FIGURE 12 is a partial view showing the magazine mounted relative to the dies;

FIGURE 13 is an end view showing the device for locating the magazine;

FIGURE 14 is a perspective view of the dog which forms part of the clutch mechanism; and

2

FIGURE 15 is a fragmentary view of the dog and the clutch operating arm.

As shown in FIGURE 1 the machine may be considered to be comprised of various components including a base A; a motor B; a magazine C; crimping means D; means for conveying energy from the motor to the dies E.

The crimping means comprises a pair of crimping dies 10, 12 slidable on a track 14 for longitudinal movement toward or away from each other (FIGURE 2). The die 12 has a bell crank 16 pivoted thereto at pin 18 with the other end journaled in a roller 20.

A cam plate 22 is eccentrically pivoted about shaft 24 and a trackway 26 in the cam 22 accommodates a roller 20. As shown in FIGURES 2 and 3, rotation of the cam 22 about the shaft 24 causes the roller 20 to ride in the trackway 26 whereby it describes a path urging the bell crank 16 in a counter-clockwise direction, causing the die 12 to move in a direction toward die 10. The die 10 has a similar bell crank 16 pivoted at one end by pin 18'; the other end secured to a roller 20' which rides in trackway 26' located in cam plate 22'. The cam 22' also rotates eccentrically in the opposite direction about the shaft 24 to cause the die 10 to move toward the die 12. A tie bar 28 provides support for pivoting each bell crank at one end thereof as well as synchronizing the dies. Thus rotation of the shaft 24 caused the dies to move between open and closed positions.

The adjustment means (FIGURES 5-7) for properly aligning the dies relative to the bell crank (and thus the cam plate) includes the pin 18 which is splined to an eccentric 30, which in turn is positioned in an eccentric opening 32 in the die link 34. One end of the die link is split as at 36 and a threaded member 38 is used to secure the die link 34 to the eccentric 30. Initially the gap 36 provides a loose fit between the die link 34 and the pin 18. The eccentric is rotated until it properly adjusts the die link 34 relative to the bell crank. Then the threaded member 38 is used to tighten the link 34 so that it firmly holds the parts in the adjusted position. The opposite die 10 is adjusted in the same manner. A finer adjustment of the dies is obtained by eccentric pins 39 and 39'.

A standard motor B is employed as a driving means, with a belt 40 and belt tightener 41 driving a flywheel 42, which in turn drives the shaft 24 via a one cycle clutch (FIGURE 11).

One Cycle Clutch

As shown in FIGURE 11, the shaft 24 normally rotates freely with respect to the flywheel 42. The clutch is comprised of a clutch plate 44 fixedly secured to the shaft 42 by means of a splined connection 46, secured in place by a set screw 47. A section of the clutch plate 44 is longitudinally slotted as at 48 to receive a clutch dog 50. A spring 52 in the clutch plate biases the dog 50 toward a clutch receiving plate 54 which is fixed to the flywheel by a pin 56. A slot 58 in the plate 54 accepts the dog 50 so that when the spring 52 is extended, the dog 50 fixedly engages a slot 58 in the clutch receiving plate 54. In this position rotation of the flywheel 42 causes rotation of the clutch and of course rotation of the shaft 24.

An operating arm 60 normally retains the dog 50 in its retracted position, i.e. with the flywheel rotating independently of the clutch or shaft. When the arm 60 is raised from the longitudinal path of the dog 50, the spring 52 urges the dog 50 toward the slot 58 in the clutch receiving plate 54 to cause engagement. After one revolution of the clutch, the arm 60 is returned to its initial position to again disengage the clutch from the flywheel.

The mechanism for actuating the operating arm 60 is illustrated in FIGURES 8-11. The arm 60 and a second arm 64 form a crank K which is pivoted at 62. A first link

66 contains a slot at right angles to the plane of the crank, and has therein a pivot pin 70 fixed to the housing which rides in the slot 68. A second pin 72 projects from the first link 66 and rides in a slot 74 in a second link 76 which is pivoted by pin 78 to the housing H. An arm 80 secures the second link 76 to a solenoid S. A spring 82 biases link 66 in a counter-clockwise direction while a spring 84 biases the crank arm 64 in a clockwise direction. A shoulder 86 on the link 66 engages the arm 64 so that movement of the link 66 relative to the pin 70 drives the crank arm 64 in a counter-clockwise direction, against the action of spring 84.

The solenoid may be operated by any convenient means, such as a foot pedal (FIGURE 1). Starting with the clutch disengaged (FIGURE 8) operation of the solenoid S urges the arm 80 away from the housing H. The link 76 is moved clockwise carrying the pin 72 with it whereby the link 66 travels in the same direction as the arm 80. The shoulder 86 bears against the arm 64 urging it in a counter-clockwise direction (FIGURE 9) so that operating arm 60 is also moved in a counter-clockwise direction. This raises the arm 60 clear of the path of the dog 58. The spring means 52 urges the dog into the slot 58 in clutch receiving plate 54. The clutch thus rotates with the flywheel thereby causing rotation of the shaft 24.

When the clutch has rotated approximately 180° (FIGURE 10) the dog 58 will bear against and depress the arm 66, thus releasing the shoulder 80 from the arm 64. The spring means 84 again urges the crank K in a clockwise direction so that the operating arm 60 returns to its initial position. Continued rotation of the clutch through the remaining 180° brings the dog into alignment with the operating arm 60 whereby it is again disengaged from the clutch receiving plate 54. A cam surface 57 on the dog 58 bears upon a beveled surface on the operating arm 60 to cause this disengagement (FIGURE 15). Spring means 82 returns link 76 etc. to their original position. A brake band (not shown) may be employed to control the speed of the clutch.

Operation

It is apparent from the foregoing that actuating of the solenoid causes the clutch to engage the flywheel, thus operating the shaft 24 through one revolution, after which it is disconnected until the solenoid is actuated again. As shown in FIGURES 2 and 3, one revolution of the shaft 24 causes one revolution of each of the cams 22 and 22'. A single revolution of the cams 22 and 22' operates the dies 10 and 12 through a complete cycle, i.e. they travel toward each other until their rollers are located on the high points of the cams wherein the dies are close enough to compress a connector positioned therein. Completion of the cycle withdraws the dies and releases the crimped connector. The one cycle clutch insures operating conditions wherein one operation of the foot pedal will cause one, and only one, actuation of the dies through the crimping cycle and return.

The feeding mechanism includes a magazine 90 which contains a plurality of chutes with a plurality of con-

nectors stacked in each chute. The magazine is supported on a trackway 92 by flanges 94 and 96. An ordinary rack 96 and pinion 98 connection is used to move the magazine along the trackway. The magazine is positioned so that one of the chutes is above the crimping position of the dies. The connectors are fed by gravity into a channel 100 which holds them in the proper crimping position. When the dies are brought together, a beveled finger 102 and 102' on each die separate the connector to be crimped from the column of connectors so that only the lowermost connector is in the crimping position. When a chute is empty, the pinion is rotated to move the rack, thus repositioning a different chute above the dies.

An oil vent 104 is provided (FIGURE 11) to lubricate the journaled bearing 106 surrounding shaft 24.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claim when viewed in their proper perspective against the prior art.

We claim:

25 A device for crimping electrical connectors including a pair of movable dies, cooperable to crimp a connector, a motor means for generating energy, linkage means between the motor means and the dies for transmitting said energy from the motor means to the dies, said linkage means comprising a fly wheel having at least one slot therein, said fly wheel driven by said motor means, a rotatable shaft journaled in said fly wheel, a clutch plate secured to said shaft and rotatable therewith, means for operating said dies by rotation of the shaft, connecting means between said clutch plate and said fly wheel comprising a slidable member on said clutch plate adapted to slide into engagement with said slot, to connect the fly wheel to the clutch plate, and arm means associated with said clutch plate normally holding said slidable member 30 disengaged from said slot, and operable to permit the connecting means to engage the slot through only one revolution of the clutch plate, and means for retaining the slidable member in the disengaged position until reset and reengaged.
